(57) **CLAIM**

The ornamental design for a stove steamer as shown and described.

DESCRIPTION

FIG. 1 is a perspective view of a stove steamer showing my new design;

FIG. 2 is another perspective view thereof;

FIG. 3 is another perspective view thereof;

FIG. 4 is a front view thereof;

FIG. 5 is a back view thereof;

FIG. 6 is a left view thereof;

FIG. 7 is a right view thereof;

FIG. 8 is a top plan view thereof;

FIG. 9 is a bottom plan view thereof; and,

FIG. 10 is an exploded perspective view of the stove steamer.

The portions shown in lower opacity and surrounded by broken lines show portions of the stove steamer that form no part of the claimed design.

1 Claim, 10 Drawing Sheets
